UNITED STATES PATENT OFFICE

JOHN H. PENNIMAN AND JAMES G. COLLINS, OF KALAMAZOO, MICHIGAN, ASSIGNORS
TO THE ATLAS PRESS COMPANY, OF KALAMAZOO, MICHIGAN

REVOLUBLE DISPLAY STAND

Application filed December 30, 1929. Serial No. 417,413.

The objects of the invention are:

First, to provide a simple, safe, portable, revolvable automobile display stand.

Second, to provide an improved construction of power driven display stand turntable for automobiles or the like.

Third, to provide an improved driving means therefor.

Fourth, to provide improved elevating means therefor.

Fifth, to provide improved control means for such elevator and driving means.

Objects pertaining to details and economies will appear from the description to follow.

A preferred embodiment of my invention is illustrated in the accompanying drawing, in which:

Fig. 1 is a plan view of the entire structure, certain concealed portions being indicated by dotted lines, and the electric motor for actuating the same being entirely omitted.

Fig. 2 is an enlarged detail sectional elevation view taken on line 2—2 of Figs. 1, 3 and 4, the elevated position being indicated by dotted lines, and the collapsed position of an adjusting jack also being shown by dotted lines in lowered position.

Fig. 3 is an enlarged detail sectional plan view, portions being shown in full lines, taken on line 3—3 of Figs. 2 and 4.

Fig. 4 is an enlarged detail sectional view on line 4—4 of Figs. 1, 2 and 3, the tapered actuating pins for the clutch being shown in full lines.

Fig. 5 is an enlarged detail sectional view of the reduction gear train taken on line 5—5 of Fig. 1.

Fig. 6 is a detail sectional elevation on line 6—6 of Fig. 2 of one of the supporting wheels.

Fig. 7 is an enlarged detail section on line 7—7 of Fig. 1, showing the detail of the carrying caster with transporting handle secured thereto.

Fig. 8 is an enlarged detail perspective view of the attaching clip for securing the head of the adjusting jack to the chassis frame.

The parts will be identified by their numerals of reference which are the same in all the views.

1 is the transporting circular base. This is carried on the yielding spring wheels 2, 2 and the pivoted spring caster wheel 3. The wheels 2, 2 are on stocks which fit in sockets 21, 21 on the base. These stocks are bifurcated and provided with wheels 22 which are held in position by pins 23 which play up and down in slots 24. Compression springs 25 are provided above these wheels.

The pivoted spring caster 3 is a precisely similar structure to wheels 2 except that it has a shank 31 with stop collar 32. The transporting handle 33 is pivoted at 34 to the shank 31. It has a compression spring 35.

The springs 25, 25 and 35 are sufficient to hold the entire structure off the floor when it is not loaded so that by means of the handle 33 the stand can be pushed or pulled into any position desired, and readily located under the body of an automobile, or other structure that it is desired to elevate and turn about to display.

A turntable 4 is provided with ball bearings 5 and turns centrally of the base 1. This has a body 41 disposed in a central bearing 42 on the base 1 and is retained against displacement by a screw collar 43. This turntable is provided with an upper platform 44 which is joined to the turntable 4 by pairs of parallel bearing plates 45, 45 on all four sides thereof.

Between these parallel plates are lever arms 6, 6 the outer ends of which are provided with anti-friction rollers 61. These levers 6 are actuated in unison and serve to raise or lower the elevating frame 7. The elevating frame 7 is rectangular in form and made of angle bar with the angles to the lower outer side of each frame bar. Centrally of each frame bar on its underside is a transverse guide 71 with a guideway 72 in which the anti-friction wheels 61 on levers 6 operate, so that when the inner ends of levers 6 are pulled down, the elevating frame is raised.

At each corner of the elevating frame we

dispose an adjusting screw jack 8, the base 81 of which is pivoted on the elongated pivot 82. The jacks are thus adjustable back and forth to proper position for engaging the frame or chassis of an automobile. The jack screws 83 are operated by little hand wheels 84. The heads 85 are provided with screw clips 86 for coupling to the chassis or frame, as clearly detailed in Fig. 8. While sliding 10 the adjustable stand under an automobile, the jacks are turned down, as indicated by the dotted lines at the right of Fig. 2.

The inner ends of the levers 6 are actuated by means of the screw 9 provided with 15 a flanged actuating nut 91 which engages rounded projections 62 on the inner ends of the levers 6.

As the screw 9 is actuated, the nut 91 is pulled down to the position indicated by 20 dotted lines in Fig. 2, or to any intermediate position. The screw 9 is actuated by the worm gear 92 which is secured to flange 93 at the bottom of the screw. The worm gear is provided with ball bearing 94 on 25 the underside of the turntable 4, so that the screw is very readily rotated centrally of the said table. The turntable is driven by means of the worm 10 on the driving shaft 101 which is actuated by a reversible electric motor 11 30 through belt drive 111, shaft 112 and reduction gear train 113.

It will thus be seen that the screw 9 can be operated in either direction from the reversible motor 11 and when it is pulled down 35 to the position indicated by dotted lines in Fig. 2, the elevating frame is raised to its highest position. Of course, to do this the turntable 4 must be held against rotation and this is done by the yoke 12 pivoted at 121 40 which is swung up into engagement with one of the levers 6. When the lever 6 swings up out of engagement with the yoke 12, the turntable is free to revolve and the turntable would be free to revolve at any point during 45 its elevation by throwing the yoke down to the position indicated by dotted lines in Fig. 2.

The friction of the parts on the screw would, when the turntable is released, permit the same to revolve but it would be subject to accidental displacement. We, therefore, provide means for locking the screw to the turntable, after the proper elevation has been attained. To do this we provide a clutch 50 13 made up of two collapsible members 131 and 132 which are semi-circular in form. These engage cooperating recess 46. These clutch members are keyed to the screw by 55 keys 133 and are held in collapsed disengaged position by the encircling spring 134 in the groove 135. There are disposed between these semi-circular sections, wedge pin members 136 with outward tapering ends 60 137, flattened at the sides, and with beveled

inner ends 138 which are flattened top and bottom.

The clutch is operated by cone 14 which is disposed in central bore 95 of the screw 9. This is actuated by plunger 141 on which 70 the cone rotates. The plunger head 142 reciprocates in the bore 95 and a ball bearing 143 is interposed between the head and the cone. The lower end of the plunger 141 is provided with an actuating knob 144 and the plunger 141 reciprocates centrally through through the ball retainer of ball bearing 145. The lower end of the plunger 141 is squared and is straddled by the bifurcated cam 146 which is controlled by the rod 75 147 having knob 148.

When it is desired to lock the elevating screw to the turntable and suppress its operation, the knob 148 is pushed in and the bifurcated cam 146 wedges and cams against 80 the knob 144, pulling the actuating cone 14 down against the inner beveled ends 138 of the actuating pins 136. This forces the same outwardly so that they wedge the clutch members 131, 132 apart into engagement with the 85 recess 46 in the top of the turntable 4, thereby locking the screw to the turntable so that actuation of the worm gear 32 from then on slowly turns the turntable and all that is supported thereby in either direction, depending on the adjustment of the reversible motor. The screw, being thus locked to the turntable, can no longer raise or lower it.

Of course, in place of a reversible motor, it would be possible to make use of a reverse gear. This is a detail, however, which we have not deemed it necessary to illustrate.

In the operation of our improved display stand, an automobile is located at the desired point for display. The body springs of the automobile are locked by a suitable clamp or by wiring so that they will not open out when the load is released by the elevating means. We then slide our improved display stand centrally under the body which is readily accomplished because the same is carried on the three rollers, one of which turns and guides the others by the transporting handle. The adjusting jacks are closed down within the frame while this locating is being done.

When the stand is in place, the turntable is rotated until the adjusting jacks 8 swing to the proper position. They are adjustable along the elongated pivots provided to accommodate them. They are then preferably placed under some angle part of the frame and secured by the clips 86. The jack screws 83 are adjusted by the hand wheel 84 to engage the frame or chassis of the automobile, and when it is thus in its lower position, it is ready for elevation.

The yoke 12 is then swung up into engagement with one of the levers 6. The electric motor is operated with the structure adjusted in position, as indicated in Fig. 2. This drives 120 125 130

the worm 10 actuating the worm gear and the elevating screw 9 which pulls down the nut 91, forcing the inner ends of the levers 6 downward and elevating the frame 7. This 5 action may be continued until the arms 6 are lifted out of the yokes 12, which occurs at the time that the nut 91 is brought down to the bottom position.

The table thus in its completely elevated 10 position, the screw, having reached the end of its travel, will be rotated gradually by the action of the worm gear and the table can be rotated in that direction indefinitely.

By reversing the gear, the table can be rotated in the opposite direction. If it is desired to lower the table, its rotation can be stopped and the yoke 12 thrown into position as soon as it will engage one of the levers 6 and the screw can be operated to elevate the 20 nut 91 to the limit of its travel, and until the automobile is dropped down to the floor again. The attendant should watch this operation and stop the motor at the required time.

25 When the display stand is completely elevated, the screw and the turntable may, if desired, be locked together by the clutch. This is accomplished by forcing the knob 148 inward, which forces the bifurcated cam 146 into engagement with the knob 144, pulling down the plunger 141, forcing the cone 14 into engagement with the beveled inner ends of the lock pins 136, forcing them outwardly so that their outward beveled ends spread the 30 clutch members into engagement with the turntable, locking the screw against any relative movement with the turntable, and thereby locking the structure for ready rotation of the turntable in either direction. The 40 screw is released from the turntable by pulling out the knob 148 which reverses the actions just described.

By thus providing means for locking the screw to the turntable, it may be locked there- 45 to at any point in its elevation, thus making it possible to lift an automobile only slightly above the floor, which is the preferred position for automobile display purposes, and then locking the screw.

50 It is an object of this machine to gradually turn and present all sides of the automobile for inspection so that a person desiring to inspect the automobile, stopping at a display window, can observe all sides and all parts in a few minutes by simply standing and observing the structure.

This turntable is useful for display purposes generally. It makes any display stand a revoluble stand by merely providing a place 60 for the introduction of our improved turntable underneath the same. Its principal use, however, is for the display of automobiles.

Having thus described our invention, what we claim as new and desire to claim by Letters Patent, is:

1. In a revoluble display stand, the combination of a portable base, carrying wheels thereunder with collapsible compression springs to yield under the load of the stand, a turntable on the said base, outwardly projecting lever arms on the said turntable fulcrumed intermediate their ends, a supporting frame disposed and arranged to be carried by the outer ends of the said lever arms, adjusting jacks on the said frame, a screw with a worm gear disposed upwardly through the said turntable with a flanged nut at its upper end for acting upon the said lever arms, a driving worm with gear for actuating the said screw, a clutch for coupling the said screw to the turntable, to turn the table when locked, and a reversible motor means for driving said worm.

2. In a revoluble display stand, the combination of a portable base, a turntable on the said base, outwardly projecting lever arms on the said turntable fulcrumed intermediate their ends, a supporting frame disposed and arranged to be carried by the outer ends of the said lever arms, adjusting jacks on the said frame, a screw with a worm gear disposed upwardly through the said turntable with a flanged nut at its upper end for acting upon the said lever arms, a driving worm with gear for actuating the said screw, a clutch for coupling the said screw to the turntable, to turn the table when locked, and a reversible motor means for driving said worm.

3. In a revoluble display stand, the combination of a portable base, carrying wheels thereunder with collapsible compression springs to yield under the load of the stand, a turntable on the said base, outwardly projecting lever arms on the said turntable fulcrumed intermediate their ends, a supporting frame disposed and arranged to be carried by the outer ends of the said lever arms, a screw with a worm gear disposed upwardly through the said turntable with a flanged nut at its upper end for acting upon the said lever arms, a driving worm with gear for actuating the said screw, a clutch for coupling the said screw to the turntable, to turn the table when locked, and a reversible motor means for driving said worm.

4. In a revoluble display stand, the combination of a portable base, a turntable on the said base, outwardly projecting lever arms on the said turntable fulcrumed intermediate their ends, a supporting frame disposed and arranged to be carried by the outer ends of the said lever arms, a screw with a worm gear disposed upwardly through the said turntable with a flanged nut at its upper end for acting upon the said lever arms, a driving worm with gear for actuating the said screw, a clutch for coupling the said screw to the turntable, to turn the table when locked, and

a reversible motor means for driving said worm.

5. In a revoluble display stand, the combination of a portable base, a turntable on the said base, outwardly projecting lever arms on the said turntable fulcrumed intermediate their ends, a supporting frame disposed and arranged to be carried by the outer ends of the said lever arms, adjusting jacks on the said frame, a screw with a worm gear disposed upwardly through the said turntable with a flanged nut at its upper end for acting upon the said lever arms, a driving worm with gear for actuating the said screw, and a reversible motor means for driving said worm.

10 6. In a revoluble display stand, the combination of a portable base, a turntable on the said base, outwardly projecting lever arms on the said turntable fulcrumed intermediate their ends, a supporting frame disposed and arranged to be carried by the outer ends of the said lever arms, a screw with a worm gear disposed upwardly through the said turntable with a flanged nut at its upper end for acting upon the said lever arms, a driving worm with gear for actuating the said screw, and a reversible motor means for driving said worm.

15 7. In a revoluble display stand, the combination of a turntable with adjustable levers thereon fulcrumed intermediate their ends, and with anti-friction wheels at their outer ends, and a supporting frame with radially disposed guideways for engaging the said wheels carried by the said levers.

20 8. In a revoluble display stand, the combination of a rectangular elevating frame with means for actuating the same, adjusting jacks towards the corners of said frame, and elongated pivots for the base of said adjusting jacks whereby the same may be swung downwardly and be adjusted in position on said pivots.

25 9. In a revoluble display stand, the combination of a rectangular elevating frame with means for actuating the same, adjusting jacks towards the corners of said frame, and pivots for the base of said adjusting jacks whereby the same may be swung downwardly and be adjusted in position on said pivots.

30 10. In a revoluble display stand, the combination of a base, a turntable thereon with suitable adjustable carrying means, an elevating screw disposed through said turntable and carried thereby, an actuating nut on the said screw to adjust said carrying means, a worm gear on said screw, a worm for driving the said screw, and a clutch to lock said screw to the turntable.

35 60 In witness whereof we have hereunto set our hands.

JOHN H. PENNIMAN.
JAMES G. COLLINS.
